UNITED STATES PATENT OFFICE

124,660

DESIGN FOR A KNIT FABRIC

Alfred L. Wagler, North Hills, Pa.

Application June 10, 1940, Serial No. 92,914

Term of patent 14 years

To all whom it may concern:

Be it known that I, Alfred L. Wagler, a citizen of the United States and a resident of North Hills, in the county of Montgomery and State of Pennsylvania, have invented a new, original, and ornamental Design for a Knit Fabric, of which the following is a specification, reference being had to the accompanying drawing, forming a part thereof.

The figure of the drawing is a plan view of a knit fabric showing my design.

I claim:

The ornamental design for a knit fabric, as shown.

ALFRED L. WAGLER.
